UNITED STATES PATENT OFFICE.

ALFRED A. ZIEGLER, OF BOSTON, MASSACHUSETTS.

BONDING DEVICE FOR RAILS.

1,116,000.

Specification of Letters Patent.

Patented Nov. 3, 1914.

Application filed June 23, 1913. Serial No. 775,277.

To all whom it may concern:

Be it known that I, ALFRED A. ZIEGLER, a citizen of the United States, residing at Boston, in the county of Suffolk and State 5 of Massachusetts, have invented an Improvement in Bonding Devices for Rails, of which the following is a specification.

This invention relates to bonding-devices for rails.

10 It is the common practice to attach the ends of the bond-wires to the rails and to form large loops which extend over the tie-plates. These loops are unsupported except at their ends and are very objectionable 15 on account of the liability of being broken, as in such event the signal-circuit is disrupted. Heretofore means have been devised for supporting the bond-wire loops between their ends, but either the wires are 20 concealed for a substantial portion of their length and hence do not admit of immediate inspection, or they are connected with the tie-plate or with the attaching-means for the tie-plate in such manner as to interfere 25 therewith and cause trouble, particularly between the men who have charge of the track, and the men who have charge of the signal-system, and, so far as I am aware no support for a bond-wire loop has ever been 30 adopted.

This invention has for its object the construction of an improved form of support for a bond-wire loop which is adapted to support the same and which does not interfere with the tie-plate or attaching-means therefor, and is exposed throughout its length for inspection.

In one embodiment of my invention the tie-plate has formed on its outer side one or 40 more grooves which are extended from end to end of the plate, which are made large enough to receive the bond-wires, and said groove or grooves are so disposed as to extend under the heads of the attaching-bolts 45 or the washers beneath the nuts on the attaching-bolts, and said groove or grooves are made of a depth slightly less than the diameter of the wire so that when the wires are arranged therein they will be impinged 50 and this affords additional electrical connection of the wires with the rails; and in another embodiment of the invention the groove or grooves are made of a depth slightly greater than the diameter of the

wire, to loosely receive the wire, and admit 55 of removal and replacement of a wire without disturbing the attaching-means.

Figure 1 is a front elevation of the adjacent end-portions of a pair of rails with a bond-wire attached thereto, the loop of 60 which is supported by means embodying this invention. Fig. 2 is a front view of the tie-plate. Fig. 3 is an enlarged transverse longitudinal section taken on the dotted line 3—3, Fig. 1. Fig. 4 is a transverse vertical 65 section taken on the dotted line 4—4, Fig. 1. Fig. 5 is a similar transverse vertical section of a modified form of my invention.

10, 10, represent the end-portions of a pair of rails; 12 the tie-plate which is secured thereto by any attaching-bolts 13, and 15 the bond-wire which is attached at its ends to said end-portions of the rails. The tie-plate has formed on its outer side or 70 face one or more grooves 20, two being here 75 shown, which are extended from end to end of the plate. Said groove or grooves are arranged near the holes for the attaching-bolts, so that when the bond-wire is arranged therein the usual washer on the attaching-bolt will extend over the groove and thus keep the bond-wire in place. In this embodiment of the invention the loop of the bond-wire is supported yet is exposed 80 throughout its length, and hence may be 85 easily and quickly inspected, and a break therein may be readily found.

In the form shown in Fig. 4 the groove or grooves which are formed in the outer side or face of the tie-plate are made of a 90 depth slightly less than the diameter of the wire and the head of the attaching-bolt or the washer thereon will engage the wires and thus hold them in place, and by impinging thereon will serve to establish an 95 electrical connection at the points of engagement which is of importance in case the wire breaks between said points. In the form shown in Fig. 5, the grooves are made of greater depth than the diameter of the 100 wire, so that the wire is loosely supported, and hence they may be removed and replaced without disturbing the attaching-bolt.

I claim:—

105 A support for bonding wires intermediate their terminal rail connections, consisting of a rail tie plate and bolts for securing the

plate in rail connecting position, said plate being formed with one or more grooves in the full length of its outer surface to receive throughout the length thereof the intermediate portions of the bond wires, said grooves extending beneath the heads of the attaching bolts.

In testimony whereof, I have signed my name to this specification, in the presence of two subscribing witnesses.

ALFRED A. ZIEGLER.
